Application June 24, 1935, Serial No. 28,080

10 Claims. (CL. 101—66)

This invention relates to a Printing device.

It is an object of this invention to provide an improved printing device which is relatively simple and inexpensive in construction and efficient in use.

Another object of the present invention is to provide a novel and improved score-printing or recording device for an amusement game apparatus of the so-called pin and marble game type.

An additional object of the present invention is to provide a novel and improved web-severing device for a score-printing or recording device adapted for use in conjunction with so-called pin and marble games.

Other objects will appear hereinafter.

The invention consists in the novel combination and arrangement of parts to be hereinafter described and claimed.

The invention will be understood best by reference to the accompanying drawings, showing the preferred form of construction and in which:

Fig. 1 is a fragmentary top plan view of a game apparatus including a preferred form of the new ticket printing and web-severing device;

Fig. 2 is a front elevational view of the new ticket-printing unit, on line 2—2 in Fig. 1, partly in section;

Fig. 3 is a view on line 3—3 in Fig. 2, partly in section and partly in top plan;

Fig. 4 is a fragmentary top plan view on line 4—4 in Fig. 2;

Fig. 5 is a side elevational view of the web-advancing device embodied in the present invention;

Fig. 6 is a fragmentary detail view on line 6—6 in Fig. 2;

Fig. 7 is a fragmentary top plan view of a coin slide latching mechanism embodied in the new ticket-printing unit;

Fig. 8 is a plan view, partly in section, on line 8—8 in Fig. 7;

Fig. 9 is a sectional detail view of the master or control plunger or "button" on line 9—9 in Fig. 7;

Fig. 10 is an elevational view, on line 1—1 in Fig. 8, of the master or control "button" or plunger, which controls the web-printing and severing operation;

Fig. 11 is a schematic wiring diagram of the electric circuit embodied in the present invention; and

Fig. 12 is an elevational view of part of the web-advancing device in the present invention.

A cabinet which embodies or houses a pre-

ferred form of the present invention is fragmentarily shown in the drawing, is therein generally indicated at 10, and includes an end wall 11, this cabinet being of the general type which is used in conjunction with so-called pin and marble games.

Slidably mounted in the end wall 11 of the cabinet 10 is a coin slide 12 and likewise slidably mounted in the end wall 11 of the cabinet 10 are a plunger or push "button" 13 and a ball 10 propelling device or plunger 13.

Provided in the coin slide 12, (Fig. 1), is a notched portion 25, (Fig. 1), and the wall which defines this notched portion 25 of the coin slide 12 is adapted to engage a vertically extending pin or post 24 which is carried by an operating member 26, (Fig. 5). This operating member 26 is pivotally mounted, as at 22, upon a horizontally extending wall 53 of a supporting frame 15, which is generally indicated at 14, and is 20 movable in a horizontal plane.

Carried by, and forming a part of, the pivotal operating member 26 is an arm 41, (Fig. 3), and this arm 41 is adapted to be moved into engagement with an electric switch contact 42, (Fig. 1), 25 so as to force the contact 42 into engagement with a contact 43.

Associated with, and arranged adjacent to, the contacts 42 and 43 is a third contact 71, (Fig. 1), which is adapted to be moved into engagement with the middle contact 43 by means of an arm 60 of a member 57, (Fig. 3), this member 57 being pivotally mounted upon the horizontal wall 53 of the supporting frame 15, for movement in a horizontal plane, and this member 57 being coaxially mounted, as at 22, with 35 or relative to the pivotal operating member 26.

Provided in the member 57, (Fig. 3), is a notched portion 55 which is latchingly engageable with an upwardly extending arm 105 of a 40 latch member 54, (Fig. 3), this latch member 54 being pivotally mounted at one end, as at 181, upon the horizontal shelf 53 and upon the bottom side of the latter and being urged in a clockwise direction (Fig. 6), by a spring 45 107.

The member 57 also includes an upwardly extending arm 92 and this arm 92 is adapted to be engaged by an arm 27 of the member 26, so as to pivot the member 57, (clockwise, Fig. 3), 50 for reasons which will be explained hereinafter.

Arranged upon the supporting frame 15 adjacent the inner end of the push "button" or plunger 13, (Fig. 1), are two normally spaced contacts 75 and 76, (Fig. 1), and likewise mount- 55

ed upon the supporting frame 15 is an electro-magnet 44. The contacts 42—43, and 71, and the contacts 15 and 76, together with the electro-magnet 44, are arranged in an electric circuit 72 (Fig. 11), which also includes a suitable current source, which may be, for example, a battery 77 of dry cells arranged in the cabinet 10.

Associated with the electromagnet 44 is a pivotal armature 45, (Fig. 2), and this armature 45 is pivotally connected, at one end (Fig. 2), to the lower end portion 46 of a vertically extending bar 47 which is pivotally mounted, adjacent its upper end, as at 48, (Fig. 2), upon the supporting frame 15.

15 A link 49, (Fig. 3), has one end connected to the pivotal bar 47 and the other end of this link 49 is attached to the end portion 50 of a horizontally extending bar 51, this bar 51 being pivotally mounted, between its ends, as at 52 upon the horizontal shelf 53 of the supporting frame 15, and being urged in a clockwise direction (Fig. 3) by a spring 110.

20 Carried by the member 57 is an upwardly extending post or pin 61, (Fig. 3), and attached to this post or pin 61 is one end portion of a coil spring 62, the other end portion of this coil spring 62 being attached to a vertically extending post or pin 63 which forms a part of the pivotal and web-severing printing device, which 25 is generally indicated at 64 (Fig. 3).

25 Associated with the present printing and web-severing unit is an inscription-receiving web 18, (Fig. 2), and the free end portion of this web 18 is guided, by means of guideways 19, which are 30 arranged upon the supporting frame 15, past the peripheral or printing surface of a printing drum 16 which is rotatably mounted upon the supporting frame 15. Bearing upon the peripheral or printing surface of the drum 16 are inking 35 rollers 17.

40 The inscription-receiving web 18 is of the perforated type and the relatively free end portion of the web 18 is moved, in a step by step movement, past the printing surface of the drum 16 by means of a web-advancing roller 20 which is rotatably mounted upon the supporting frame 15, (Fig. 2). Provided on the periphery of the web-advancing roll 20 are lugs 21, (Fig. 2), and these lugs 21 are engageable in perforations 45 50 (not shown) which are formed in the web 18.

55 The severing device embodied in the present apparatus comprises a relatively movable knife 68 which is pivotally mounted as at 65 (Fig. 4) upon a lateral extension or arm 66 of the supporting frame 15. The web-severing knife also 60 includes a relatively stationary blade 70 which is fixedly attached to the arm 66, and the web-printing device comprises a platen or pressure member 85 which is coaxially mounted, at 65, 65 with the movable element 68 of the web-severing device 68—70, and the pressure member 85 and the movable element 68 of the web-severing device are interconnected by a vertically extending pin or post 63 to which one end of the coil spring 62 is attached, (Figs. 3 and 4), and by reason of this arrangement the coil spring 62 urges the movable element 68 of the web-severing knife 68—70 and the pressure member 70 (counterclockwise, Figs. 3 and 4) into engagement with the relatively free end portion of the web 18, so as to perform the score-printing and web-severing operations.

75 The web-severing knife 68—70 is arranged above the platen or pressure member 85 and the latter includes a relatively soft or resilient por-

tion 67 which is engageable with the lower or free end portion of the web 18 so as to force the latter into printing engagement with the printing drum 16 to effect the printing operation.

Pivotedly mounted at one end upon the shaft 5 65, coaxially with the movable element 68 of the web-severing knife and the platen or pressure member 85, and for movement in a horizontal plane, is a switch-operating arm 86, (Fig. 4), which is adapted to engage the contact 75 10 so as to force the latter into engagement with the contact 76. Attached to the relatively free or outer end of this switch-operating arm 86, (Fig. 4), is one end of a coil spring 109, the other end of this coil spring 88 being attached to the 15 vertically extending pin or post 63 which interconnects the movable element 68 of the web-severing knife 68—70, (Fig. 4), and the platen or pressure member 85—67 (Fig. 3).

Provided in the peripheral edge of the platen 20 or pressure member 85—67 (Fig. 3) is a notched portion 74 and latchingly engageable in this notched portion 74 is an upwardly extending arm 87 of the pivotal latch bar 50—51, this notched portion 74 of the platen 85—67 being 25 urged into engagement with the arm 87 of the latch bar 50—51 by the coil spring 62 which urges both the movable element 68 of the web-severing knife and the platen or pressure member 85—67 (in a counterclockwise direction, 30 Fig. 3).

The pivotal operating member 26 has a laterally extending arm 27 and depending from this arm 27 is an extension 28, (Figs. 5 and 12). Pivotedly connected to the depending extension 35 28 of the arm 27 is a link 30 which is pivotally connected at one end, as at 29, (Figs. 3 and 12) to a cam 33. This cam 33 is rotatably and loosely mounted, that is "floats" upon a horizontal shaft 34 which is journaled in the support- 40 ing frame 15, for movement in a vertical plane.

Pivotedly mounted at one end, as at 31, upon the cam 33, (Fig. 5), is a pawl 32. Fixed upon this shaft 34, adjacent to the cam 33 are two ratchets 35 and 99, (Fig. 5), and the web-advancing roll 45 20 is likewise fixed upon the shaft 34. Engageable with the teeth of the outer ratchet 35, (as seen in Fig. 5), is a dog 37 which is pivotally mounted at one end, as at 39, upon the supporting frame 15, (Fig. 4), and engageable with 50 the teeth of the inner ratchet 99, (as seen in Fig. 5), is a dog 102, (Fig. 5), which is pivotally mounted at its lower end, as at 78, upon the supporting frame 15, (Fig. 5). The pawl 32, which is carried by the cam 33, (Fig. 5), is like- 55 wise engageable with the teeth of the inner ratchet 99.

Having its radially inner end attached to the shaft 34 (Fig. 5), and having its radially outer end attached to the dog 102 is a coil spring 89. 60 Similarly, a coil spring 90 has its radially inner end attached to the shaft 34 and its radially outer end attached to the dog 37, and in a like manner, a coil spring 91 has its radially inner end attached to the shaft 34 and its radially 65 outer end attached to the pawl 32, (Fig. 5).

Attached to the cabinet wall 11 on the inner side thereof is a guide 79, (Figs. 7 and 8), and slidably mounted in this guide 79 is a latch bar 80. This latch bar 80 has an angled arm 84 70 which is engageable in a notched portion 82 which is provided in one longitudinal edge of the coin slide 12, (Figs. 7 and 8). The slide bar 80 is normally urged, by a resetting spring 83 in a direction, (right to left, Fig. 7, left to right, 75

Fig. 8) to move its angled or offset arm 84 into latching engagement with the notched portion 82 of the coin slide 12.

The inner end portion of the plunger 73 is 5 slidably projected through an opening 88 which is formed in the latch bar 80, (Figs. 8 and 10), and through a corresponding opening which is 10 formed in the guide 79, and the plunger 73 is normally urged outwardly, relative to the cabinet 10 wall 11 in which it is mounted, by a coil spring 103 arranged thereon, (Fig. 10). Provided on 15 the plunger 73 is a beveled annular shoulder 104 which is engageable with the wall which defines the opening 88 in the slideable latch bar 80, it being noted, (Fig. 8), that the axial center of the plunger 73 is eccentric relative to the center of the opening 88 in the slideable latch bar 80.

Provided in the plunger 73—104 is a notched portion 93, (Figs. 9 and 10), and the wall of the 20 latch bar 80 which defines the opening 88 therein is latching engageable in this portion 93 of the plunger or push button 73 so as to latch the slide bar 80 in inwardly extended position, (as in dotted lines, Fig. 10), against the action of its 25 resetting spring 103.

The latch bar 80 has a laterally extending arm 94, (Fig. 7), and this arm 94 has an upwardly extending portion 96.

Pivotedly mounted, at one end, as at 97, upon a 30 lateral extension 100 of the coin slide 12, (Fig. 7), is a trip or detent 95 and attached to the relatively free end portion of this member 95 is a coil spring 98 which urges the detent 95 (counterclockwise, Fig. 7) into engagement with the 35 upwardly extending portion 96 of the arm 94 of the slideable latch bar 80.

Operation

Balls are propelled onto the inclined playing 40 board (not shown) of the cabinet 10, by the plunger 13, and if they enter into a ball exit or scoring opening or pocket in the inclined playing board they actuate a conventional mechanism for advancing the printing drum 16 a predetermined 45 circumferential distance away from its initial or zero position, and the printing drum 16 is thus advanced in accordance with the score of the game made by the player.

When the player completes a game he pushes 50 inwardly upon the push button or plunger 73, thereby causing the inner end portion of the push button or plunger 73 to engage the contact 75 and thus move the latter into engagement with the contact 76, thereby closing the electric circuit 72, (Fig. 12), to the electromagnet 44; it 55 being understood that the switch 42—43—71, (Figs. 1 and 11), has previously been closed by the operation of the coin slide 12 and associated members 26—41 and 57—60.

When the circuit 72 to the electromagnet 44 is thus closed, by the operation of the plunger or push button 73, it attracts its armature 45, and this movement of the armature 45 pivots the vertical armature 46—47 (counterclockwise, Fig. 2), and this movement of the vertical armature 46—47 acts, through the medium of the link 49, to pivot the latch bar 50—51 at 52, (counterclockwise, Fig. 3), thus moving the upwardly extending arm 87 thereof out of latching engagement with the notched portion 74 of the platen or impression-transmitting member 85—67; whereupon the tensioned coil spring 62 urges the platen or pressure member 85—67, and the movable element 68 of the web-severing knife 68—70, 70 (in a counterclockwise direction, Figs. 3 and 4) thereby moving the relatively soft or resilient portion 67 of the platen 85—67 into engagement with the relatively free end portion of the web 18, and thus moving the free end portion of the web 18 into engagement with the inked peripheral surface of the printing drum 16 to effect the printing operation.

When the tensioned coil spring 62 acts upon the platen or pressure member 85—67 to pivot the latter, (counterclockwise, Fig. 3), into engagement with the free end portion of the web 18, it also acts upon the movable element 68 of the web-severing knife 68—70 to pivot the latter (counterclockwise, Fig. 4), thereby moving the cutting edge portion or arm 68 of the knife 68—70 15 into engagement with the relatively free end portion of web 18, which in turn is thus urged into engagement with the relatively stationary portion 70 of the web-severing knife 68—70, and in this manner the printed portion or strip of the 20 web 18 is severed from the body of the same, whereupon the thus printed and severed strip is delivered exteriorly of the cabinet 10 to the player by means of a suitable delivery chute (not shown) but which may be provided in the cabinet 25 10.

The foregoing movement of the bar 50—59 (clockwise, Fig. 6) causes the arm 59 thereof to engage one edge of the latch bar 54, thereby pivoting the latch bar 54 at 101 (counterclockwise, Fig. 3, clockwise, Fig. 4) and thus moving the upwardly extending arm 105 of the latch bar 54 out of latching engagement with the notched portion 55 of the member 56—57.

When the notched portion 55 of the member 56—57 is thus released from latching engagement with the angled end portion 105 of the latch bar or keeper 54, the tensioned coil spring 62 acts upon the member 57 to pivot the latter, at 22, (counterclockwise, Fig. 3). During this 40 movement of the member 57, (counterclockwise, Fig. 3) the arm 60 thereof moves out of engagement with the contact 71, (Fig. 1), thus allowing the contact 71 to move, by its own resiliency, out of engagement with the contact 43, and thus 45 opening the switch 42—43—71 and the circuit 72 to the electromagnet 44, and, as will be explained presently, this circuit 72 is not closed again until a proper coin or token has been inserted into the coin-aperture of the coin slide 12 and the latter 50 has been moved from its initial or coin-receiving position (as in Fig. 1), to coin-discharging position, and the player has operated the push button or plunger 73.

When a coin or token of the proper size, denomination, etc., is inserted into the coin-receiving aperture of the coin slide 12 and the latter is pushed inwardly (bottom to top, Fig. 1) from coin-receiving position to coin-discharging position, that portion of the coin slide 12 which defines the wall of the notched portion 25 therein engages the upstanding post or pin 24 which is carried by the pivotal member 26, and thereby pivots the member 26 (clockwise, Fig. 3), against the action of its resetting spring 40. During this 60 movement of the member 26 (clockwise, Fig. 3) the arm 27 thereof engages the upwardly extending arm 92 of the member 56—57 (Fig. 3) and thereby pivots the latter (clockwise, Figs. 1 and 3), against the action of its resetting spring 108, 70 thus moving the arm 60 thereof into engagement with the contact 71 (Fig. 1) and thereby forcing the contact 71 into engagement with the contact 43.

When the coin slide 12 is released and is re- 75

tracted, or returned, to its initial or coin-receiving position, (as in Fig. 1), by means of a resetting spring 106, the coil spring 62 acts upon the member 56-57 to pivot the same (counterclockwise, Fig. 3), thereby moving the notched portion 55 thereof into latching engagement with the upwardly extending arm 105 of the latch member 54, and in this manner the member 56-57 is latched (as in full line position, Fig. 3) 10 with the arm 60 thereof disposed in engagement with the contact 71, and with the contact 71 disposed in engagement with the contact 43.

At the same time, that is, when the coin slide 12 is released, and is returned to its initial or coin-receiving position (as in Fig. 1), the tensioned coil spring 40 acts upon the pivotal member 26-27-41, to pivot the latter (counterclockwise, from dotted to full line position, Fig. 3), thereby moving the arm 41 thereof into engagement with the contact 42 and thus forcing the contact 42 into engagement with the contact 43.

It will thus be seen that when the coin slide 12 has completed a full inward movement or operative stroke and has returned to its initial or coin-receiving position, the arm 60 of the member 57 is disposed in engagement with the contact 71 and the arm 41 of the member 26 is disposed in engagement with the contact 42, and the switch 42-43-71 is closed.

Accordingly, when the player operates the plunger or button 73, that is, when the same is pushed inwardly, (bottom to top, Fig. 10), the inner end portion 74 of the plunger 73 engages the contact 75, thereby closing the circuit 72 to the electromagnet 44, (Fig. 11), whereupon the electromagnet 44 attracts its armature 46-47 and the latter acts, through the medium of the link 49, to release the angled or upwardly extending arm 81 of the bar 50-51 from latching engagement with the notched portion 74 of the platen 85-87, whereupon the spring 62 pivots the platen 85-87 and the web-severing knife 68-70 (counterclockwise, Figs. 3 and 4), respectively, to effect the printing and web-severing operations.

The slide bar 80 is normally urged in a direction (left to right, Fig. 8, right to left, Fig. 7) to move the angled arm 84 thereof into latching engagement with the notched portion 82 of the coin slide 12 and the coin slide 12 is normally latched against movement by the engagement of the arm 84 of the slide bar 80 in the notched portion 82 thereof.

However, when the plunger or push button 73 is pushed inwardly, (bottom to top, Fig. 10), the beveled annular shoulder 104 thereof engages the wall which defines the opening 88 in the slide bar 80, thereby sliding the slide bar 80 (right to left, Fig. 8) and thus moving the angled arm 84 of the slide bar 80, against the action of the spring 83, out of latching engagement with the notched portion 82 of the coin slide 12, and the slide bar 80 is latched in this position, that is, with the arm 84 thereof disposed out of latching engagement with the notched portion 82 of the coin slide 12, by the engagement of the wall of the slide bar 80 which defines the opening 88 therein with the notched portion 93 of the plunger or push button 73, (Figs. 8, 9 and 10).

However, when the coin slide 12 is pushed in (bottom to top, Fig. 7), the pivotal detent 95 carried thereby engages the upwardly extending portion 96 of the arm 94 of the slide bar 80, whereupon the detent 95 is pivoted at 97 (clockwise, Fig. 7), 75 against the action of its resetting spring 98, and

when the detent 95 passes the upwardly extending portion 96 of the arm 94 of the latch bar 80, the spring 98 returns the detent 95 (counterclockwise, Fig. 7), back into its initial position, as in Fig. 7. However, when the coin slide 12 is retracted or returned to its initial position (top to bottom, Fig. 7), the detent 95 again engages the upwardly extending portion 96 of the arm 94 of the slide bar 80, and during this engagement the detent 95 acts a cam and moves the slide bar 80 (left to right, Fig. 7), thus moving the wall of the slide bar 80 which defines the opening 88 therein out of latching engagement with the notched portion 93 of the plunger or push button 73, whereupon the resetting spring 103 on 15 the plunger 73 returns the latter to its initial position (from dotted to full line position, Fig. 10).

The contact 75 then moves, by its own resiliency, out of engagement with the contact 76 and the circuit 72 (Fig. 11) to the electromagnet 44 is thus 20 opened and remains open until the coin slide 12 and the members 57-60 and 26-41 have been operated to close the switch 42-43-71 and the push button or plunger 73 has been operated to close the switch 75-76.

However, when the coin slide 12 reaches its initial or coin-receiving position (as in Figs. 1 and 7), the spring 83 again urges the slide bar 80 in a direction (right to left, Fig. 7, left to right, Fig. 8), to move the arm 84 thereof into latching 30 engagement with the notched portion 82 of the coin slide 12.

It will thus be noted, that by reason of the foregoing relationship of the push button 73, latch bar 80-84, and notched portion 82 of the coin 35 slide 12, it is necessary for the player to operate the push button or plunger 73, that is, to push in on the same, so as to release the arm 84 of the slide bar 80 from latching engagement with the notched portion 82 of the coin slide 12, before the 40 coin slide 12 may be operated, thus assuring that the printing and web-severing unit are disposed in their initial and proper position before the player commences to play.

When the coin slide 12 is pushed in, the notched portion 25 thereof engages the pin or post 24 on the pivotal member 26 and thereby pivots the member 26 (clockwise, Fig. 3), as hereinbefore explained. This movement of the member 26 (clockwise, Fig. 3), tensions the spring 40 and causes the arm 27 of the member 26 to move the link 30 (right to left, Fig. 3, left to right, Fig. 12). This movement of the link 30 (left to right, Fig. 12) acts upon the cam 33 to rotate the latter 55 (counterclockwise, Fig. 12) upon the shaft 34. This movement of the cam 33 (counterclockwise, Fig. 12) causes the rise 89 thereon to engage the latch dog 37, thereby pivoting the latch dog 37 at 38 (clockwise, Fig. 5) out of engagement 60 with the teeth of the outer ratchet 35 (Fig. 5). Accordingly, when the coin slide 12 is retracted the tensioned spring 40 acts upon the member 26 to pivot the latter (counterclockwise, Fig. 3) and during this movement the member 26 acts, 65 through the link 30, to rotate the cam 33 (clockwise, Figs. 5 and 12). During this movement of the cam 33 (clockwise, Figs. 5 and 12), the pawl 32 which is carried by the cam 33 engages the teeth of the inner ratchet 99, and the shaft 34 and the web-advancing roll 20 which is attached to the shaft 34, (clockwise, Fig. 5), thus advancing the web 18 relative to and past the peripheral and inked surface of the printing drum 16, and 75

past the cutting edge or arm 70 of the web-severing knife 68—70.

During the foregoing motion of the cam 33 (counterclockwise, Fig. 12), the dog 102, being 5 disposed in engagement with the inner ratchet 99, prevents the same and the web-advancing roll 20 from being rotated (in a counterclockwise direction, as seen in Fig. 5), and the engagement of the dog 37 being normally disposed in 10 engagement with the outer ratchet 35 prevents rotation of the latter and the web-advancing roll 20 (clockwise, Fig. 5), until the cam 33 has been operated to lift the dog 37 out of engagement with the ratchet 35.

15 When the platen or pressure member 85—67 is moved into effective or pivoting position, and the movable element 68 of the web-severing knife 68—70 is moved into effective or cutting position, the coil spring 109 acts upon the arm 86, (Fig. 4), 20 to pivot the same (counterclockwise, Fig. 4), into engagement with the contact 75 and the contact 76 is thus retained in engagement with the contact 76, and the circuit 72 is thus kept closed, so that even though the contact 75 might, by its 25 own resiliency tend to move out of engagement with the contact 76, after having been moved into engagement with the contact 76, by the movement of the push button 73, the engagement of the arm 86 with the contact 75, taking place 30 simultaneously with the printing and web-severing operations, assures that the contacts 75 and 76 will be held in engagement with each other and that the circuit 72 to the electromagnet 44 will be kept closed, when the push button 73 is 35 pushed in, thereby assuring that the electro-magnet 44 and the parts released thereby may perform the printing and web-severing operations.

As used hereinafter in the claims the term support is intended to include not only the supporting 40 frame 15 but also the supporting wall 11 of the cabinet 10 and in which wall the actuating member or coin slide 12 and the actuating member or plunger 73 are slidably mounted.

While we have illustrated and described the 45 preferred form of construction for carrying our invention into effect, this is capable of variation and modification, without departing from the spirit of the invention. We, therefore, do not wish to be limited to the precise details of construction set forth, but desire to avail ourselves of such variations and modifications as come within the scope of the appended claims.

Having thus described our invention what we 50 claim as new and desire to protect by Letters Patent is:

1. A printing and web-severing unit comprising: a supporting frame; a printing drum rotatably mounted upon said supporting frame; an actuating member and a plunger; a platen and a web-severing knife pivotally mounted upon said 55 supporting frame; means coacting with the said actuating member, when the latter is operated, to advance the relatively free end portion of an inscription-receiving or score ticket web relative to and past said platen and web-severing knife and between the same and said printing drum; means urging said platen and said web-severing knife into engagement with said inscription-receiving web; means normally 60 latching said platen and said web-severing knife out of engagement with said inscription-receiving web, or ineffective position, against the action of said urging means; and means for releasing said latching means from latching 65 engagement with said platen and said web-sever-

ing knife including an electromagnet and an electric circuit for controlling the operation of said electromagnet; said circuit including two switches arranged therein in series; means coacting with the said actuating member, when the latter is operated, to close one of said switches; and the other of said switches being closed by operation of said plunger so as to close the said circuit to said electromagnet and thus move said 70 latching means out of latching engagement with said platen and said web-severing knife so as to allow the same to be moved into engagement with said web by said urging means.

2. A score-printing unit comprising: a support; a printing drum rotatably mounted upon said support; an actuating member and a plunger slidably mounted on said support; a platen pivotally mounted upon said support; means coacting with the said actuating member, when the latter is operated, to advance the relatively free end portion of an inscription-receiving or score ticket web relative to and past said platen and between the same and said printing drum; means urging said platen into engagement with said inscription-receiving web; means normally latching said platen out of engagement with said inscription-receiving web, or in ineffective position, against the action of said urging means; and means for releasing said latching means from latching engagement with said platen including 25 an electromagnet and an electric circuit for controlling the operation of said electromagnet; said circuit including two switches arranged therein in series; means coacting with the said actuating member, when the latter is operated, to close one 30 of said switches; and the other of said switches being closed by operation of said plunger so as to close the said circuit to said electromagnet and thus move said latching means out of latching engagement with said platen so as to allow 35 the same to be moved into engagement with said inscription-receiving web by said urging means.

3. A score-printing and web-severing unit comprising: a support; a printing drum rotatably mounted upon said support; two manually operated 40 actuating members slidably mounted upon said support; a platen and a web-severing knife movably mounted upon said support; means coacting with one of the said actuating members, when the latter is operated, to advance the 45 relatively free end portion of an inscription-receiving web relative to and past said platen and web-severing knife and between the latter and said printing drum; means urging said platen and said web-severing knife into engagement with said inscription-receiving web; means normally latching said platen and said web-severing knife out of latching engagement with said inscription-receiving web, against the action of 50 said urging means; and means for releasing said latching means from latching engagement with said platen and said web-severing knife, so as to allow the same to be moved into engagement with said inscription-receiving web, under the action of said urging means, comprising an electric circuit including two switches arranged 55 therein in series; means coacting with the said one of said actuating members, when the latter is operated, to close one of said switches; and the other of said switches being closed by operation of the other of said actuating members.

4. A score-printing unit comprising: a support; a printing drum rotatably mounted upon said support; two manually operated actuating members slidably mounted upon said support; a platen 75

- movably mounted upon said support; means co-acting with one of said actuating members, when the latter is operated, to advance the relatively free end portion of an inscription-receiving web 5 relative to and past said platen and between the latter and said printing drum; means urging said platen into engagement with the inscription-receiving web; means normally latching said platen out of latching engagement with said inscription-receiving web, against the action of said urging means; and means for releasing said latching means from latching engagement with said platen so as to allow the same to be moved into engagement with said web, under the action 10 of said urging means, comprising an electric circuit including two switches arranged therein in series; means coacting with the said one of said actuating members, when the latter is operated, to close one of said switches; and the other 15 of said switches being closed by operation of the other of said manually operated actuating members.
5. A score-printing and web-severing unit comprising: a support; a printing drum rotatably mounted upon said support; an actuating member and a plunger; a platen and a web-severing knife pivotally mounted upon said support; means coacting with the said actuating member, when the latter is operated, to advance the relatively free end portion of an inscription-receiving or score ticket web relative to and past said platen and web-severing knife and between the same and said printing drum; means urging said platen and said web-severing knife into engagement with said web; means normally latching said platen and said web-severing knife out of engagement with said web, or in ineffective position, against the action of said urging means; and means for releasing said latching means from latching engagement with said platen and said web-severing knife including an electromagnet and an electric circuit for controlling the operation of said electromagnet; said circuit including two switches arranged therein in series; means coacting with the said actuating member, when the latter is operated, to close one of said switches; the other of said switches being closed by operation of said plunger so as to close the said circuit to said electromagnet and thus move said latching means out of latching engagement with said platen and said web-severing knife so as to allow the same to be moved into engagement with said web by said urging means; and means for latching the said actuating member against operation; said last-named means being released from latching engagement with said actuating member by movement of said plunger away from its normal or initial position.
6. A score-printing unit comprising: a support; a printing drum rotatably mounted upon said support; an actuating member and a plunger slidably mounted upon said support; a platen pivotally mounted upon said support; means coacting with the said actuating member, when the latter is operated, to advance the relatively free end portion of an inscription-receiving or score ticket web relative to and past said platen and between the same and said printing drum; means urging said platen into engagement with said web; means normally latching said platen out of engagement with said web, or in ineffective position, against the action of said urging means; means for releasing said latching means from

latching engagement with said platen including an electromagnet and an electric circuit for controlling the operation of said electromagnet; said circuit including two switches arranged therein in series; means coacting with the said actuating member, when the latter is operated, to close one of said switches; the other of said switches being closed by operation of said plunger so as to close the said circuit to said electromagnet and thus move said latching means out of latching engagement with said platen so as to allow the same to be moved into engagement with said web by said urging means; and means for latching the said actuating member against operation; said last-named means being released from latching engagement with said actuating member by movement of said plunger away from its normal or initial position.

7. A score printing and web-severing unit comprising: a support; a printing drum rotatably mounted upon said support; two manually operated actuating members slidably mounted upon said support; a platen and a web-severing knife movably mounted upon said support; means coacting with one of the said actuating members, when the latter is operated, to advance the relatively free end portion of an inscription-receiving web relative to and past said platen and web-severing knife and between the latter and said printing drum; means urging said platen and said 20 web-severing knife into engagement with said inscription receiving web; means normally latching said platen and said web-severing knife out of engagement with said inscription-receiving web, against the action of said urging means; means for releasing said latching means from latching engagement with said platen and web-severing knife, so as to allow the same to be moved into engagement with said web, under the action of said urging means, comprising an electric circuit including two switches arranged therein in series; means coacting with the said one of said actuating members, when the latter is operated, to close one of said switches; the other of said switches being closed by operation of the other of said manually operated actuating members; and means for latching the said one of said actuating members against operation; said last-named means being released from latching engagement with the said one of actuating members by movement of the other of said actuating members away from its normal or initial position.

8. A score-printing unit comprising: a support; a printing drum rotatably mounted upon said support; two manually operated actuating members slidably mounted upon said support; a platen movably mounted upon said support; means coacting with one of the said actuating members, when the latter is operated, to advance the relatively free end portion of an inscription-receiving web relative to and past said platen and between the latter and said printing drum; means urging said platen into engagement with said inscription-receiving web; means normally latching said platen out of latching engagement with said inscription-receiving web; against the action of said urging means; means for releasing said latching means from latching engagement with said platen so as to allow the latter to be moved into engagement with said web, under the action of said urging means, comprising an electric circuit including two switches arranged therein in series; means coacting with the said one of said actuating mem- 75

bers, when the latter is operated, to close one of said switches; the other of said switches being closed by operation of the other of said actuating members; and means for latching the said one of said actuating members against operation; said last-named means being released from latching engagement with the said one of said actuating members by movement of the other of said actuating members away from its normal or initial position.

9. A score-printing and web-severing unit comprising: a support; a printing drum rotatably mounted upon said support; an actuating member and a plunger slidably mounted upon said support; a platen pivotally mounted upon said support; means coacting with the said actuating member, when the latter is operated, to advance the relatively free end portion of an inscription-receiving or score ticket web relative to and past said platen and web-severing knife and between the same and said printing drum; means urging said platen and said web-severing knife into engagement with said web; means normally latching said platen and said web-severing knife out of engagement with said web, or in ineffective position, against the action of said urging means; means for releasing said latching means from latching engagement with said platen and said web-severing knife including an electromagnet and an electric circuit for controlling the operation of said electromagnet; said circuit including two switches arranged therein in series; means coacting with the said actuating member, when the latter is operated, to close one of said switches; the other of said switches being closed by operation of said plunger so as to close the said circuit to said electromagnet and thus move said latching means out of latching engagement with said platen and said web-severing knife so as to allow the same to be moved into engagement with said web by said urging means; means for latching the said plunger in inwardly extended or effective position; and means coact-

ing with the said actuating member, when the latter is moved away from its normal or initial position to release said last-named latching means from latching engagement with said plunger so as to permit the latter to return to its normal or initial position.

10. A score-printing unit comprising: a support; a printing drum rotatably mounted upon said support; an actuating member and a plunger slidably mounted upon said support; a platen pivotally mounted upon said support; means coacting with the said actuating member, when the latter is operated, to advance the relatively free end portion of an inscription-receiving or score ticket web relative to and past said platen and between the same and said printing drum; means urging said platen into engagement with said web; means normally latching said platen out of engagement with said web, or in ineffective position, against the action of said urging means; means for releasing said latching means from latching engagement with said platen including an electromagnet and an electric circuit for controlling the operation of said electromagnet; said circuit including two switches arranged therein in series; means coacting with the said actuating member, when the latter is operated, to close one of said switches; the other of said switches being closed by operation of said plunger so as to close the said circuit to said electromagnet and thus move said latching means out of latching engagement with said platen so as to allow the same to be moved into engagement with said web by said urging means; means for latching the said plunger in inwardly extended or effective position; and means coacting with the said actuating member, when the latter is moved away from its normal or initial position to release said last-named latching means from latching engagement with said plunger so as to permit the latter to return to its normal or initial position.
